THE NORRIS PETERS CO., PHOTO-LITHO., WASHINGTON, D. C.

UNITED STATES PATENT OFFICE.

SANFORD C. PITNEY, OF QUINCY, AND FREDERICK C. HANSEN, OF FREEPORT, ILLINOIS; SAID HANSEN ASSIGNOR TO SAID PITNEY.

SHUTTER-WORKER.

SPECIFICATION forming part of Letters Patent No. 593,854, dated November 16, 1897.

Application filed October 7, 1897. Serial No. 654,479. (No model.)

To all whom it may concern:

Be it known that we, SANFORD C. PITNEY, residing at Quincy, Adams county, and FREDERICK C. HANSEN, residing at Freeport, Stephenson county, State of Illinois, citizens of the United States, have invented certain new and useful Improvements in Shutter-Workers; and we do declare the following to be a full, clear, and exact description of the invention, such as will enable others skilled in the art to which it appertains to make and use the same, reference being had to the accompanying drawings, and to the figures of reference marked thereon, which form a part of this specification.

This device relates to those shutter-workers adapted to be operated from the inside of the house.

The object sought to be accomplished is to lock or hold the shutter or blind tight against the side of the house when the blind is open or to hold it in close contact with the opposite shutter when the blind is closed, in such a manner that the blind cannot be shaken or rattled by the wind.

To this end the invention consists in the peculiar features and combinations of parts adapted to be used in connection with the shutter-worker shown and described in the copending application of Sanford C. Pitney, bearing Serial No. 624,202, filed June 24, 1897, all of which will be more fully described hereinafter and pointed out in the claims.

In the accompanying drawings, Figure 1 represents a top view of our complete invention, in which the holding-lever is shown depressed and in locking adjustment; Fig. 2, a side elevation of the holder alone, as when out of action, dotted lines representing the position of the parts when the holding-lever is raised to vertical and horizontal positions; and Fig. 3, a detail view of the cam plate or member in which the locking-cams operate.

The numeral 1 represents a blind, and 2 and 3 beveled segments operating in connection with the hinge members 4 and 5. These hinge members are actuated by a horizontal squared spindle extending through a window-casement and having at its inside end a locking and operating handle 6. This handle is rotatable with the spindle and is hinged to swing

up and down on the outer end of a sleeve 7, squared inside to fit over the squared end of the spindle, so as to revolve with it. This sleeve is also provided with a pair of horizontally-projecting lugs 8', having flat interior walls, between which fits a flat-faced arm 9, made an integral part of the handle, so that the two constitute a lever. This arm 9 is held between the lugs by a screw 10, which forms the axis or fulcrum of the handle. Cast integral with the arm 9 are what may for convenience be termed "right" and "left" cams or "inclined planes" 11 and 12, which are adapted to operate in cam-slots 13 and 14, formed in an escutcheon, plate, or member 15, fixed to the window-casement on the inside. This fixed plate is provided with an integral collar on its back, and this collar bears against a collar 16 on the sleeve. The parts should be so timed that when the blind has been thrown back as far as it can be by merely rotating the spindle the cams will come opposite the cam-slots and in position to enter them when the handle is turned up or down.

The operation of the foregoing mechanism on a right-hand shutter is as follows: Having grasped the handle and revolved the spindle from right to left until the blind has closed loosely against the opposite blind, the handle should be lowered, whereupon the lower cam 12 will rise, enter the left-hand cam-slot 14, and, sliding against its wall, will impart a rotary motion to the sleeve, and hence the spindle and the segments, thereby locking the blind tightly against its mate. When the shutter has been thrown back open against the side of the building, the lifting of the handle into vertical position will turn the spindle in the opposite direction and the blind will be firmly held against it. When thus held, the blind cannot vibrate and make a noise and there is no danger of the wind getting behind it and slamming it shut during a storm.

Having thus described the invention, what we claim is—

1. In combination with a shutter-worker, a spindle or shaft adapted to be turned to operate the shutter, a hinged and rotatable handle provided with one or more cams, a relatively fixed plate or member having one or more cam-surfaces against which the cam op-

erates to revolve the spindle, substantially as described.

2. In a shutter-worker, a manipulating-handle provided with one or more cams, in combination with a fixed member having cam-surfaces, and a spindle to which the handle is attached, substantially as described.

3. In a shutter-worker, the combination with a spindle, and gearing substantially as described, of a sleeve adapted to fit over the end of the spindle, a pair of lugs projecting from the sleeve, a manipulating-handle having an arm hinged between the lugs, right and left cams on the arm, and a relatively

fixed plate or member provided with slots to receive the cams when the handle is raised or lowered.

In witness whereof we affix our signatures in presence of two witnesses.

SANFORD C. PITNEY.
FREDERICK C. HANSEN.
